(57) **CLAIM**

The ornamental design for a surgical drape as shown and described.

DESCRIPTION

FIG. 1 is a perspective view of a top side of the surgical drape in accordance with my new design;

FIG. 2 is a perspective view of a bottom side thereof;

FIG. 3 is a plan view of the top side thereof;

FIG. 4 is a plan view of the bottom side thereof;

FIG. 5 is a side elevation view thereof;

FIG. 6 is a back side elevation view thereof; and,

FIG. 7 is a front side elevation view thereof.

The broken lines in the figures illustrate portions of the surgical drape that form no part of the claimed design. The side elevation view of the surgical drape represent the right and left sides of the surgical drape, that mirror each other.
